Attorney.

UNITED STATES PATENT OFFICE.

GEORGE EDWARD KINCH, OF QUIRINDI, NEW SOUTH WALES, AUSTRALIA.

AUTOMATIC SHUTTER FOR SANITARY CLOSET-SEATS.

1,303,564.

Specification of Letters Patent. Patented May 13, 1919.

Application filed October 14, 1915. Serial No. 55,850.

To all whom it may concern:

Be it known that I, GEORGE EDWARD KINCH, subject of the King of Great Britain and Ireland, residing at "The Poplars", 5 Quirindi, New South Wales, Australia, have invented new and useful Improvements in Automatic Shutters for Sanitary Closet- Seats, of which the following is a specification.

10 This invention relates to sanitary closets and consists in certain improvements in seat shutters and in automatic mechanism for opening and closing said shutters.

The shutter comprises a pair of plates 15 with lapping edges, movable transversely away from or toward each other in slides below the seat by pressure applied above the seat. The automatic operating mechanism comprises two slotted lever arms, and 20 spring retarded connections to said lever arms from a canting portion of the seat.

The shutter leaves are formed with lapping flanges which serve to stiffen them and operate to cover clearance spaces and so insure a substantially close cover for the pan, 25 preventing access of flies into it. The slides in which the shutters work are mounted on a pair of flat frame bars which are each fixed to the underside of the seat by two 30 screws, one of which is set in a forked end or slotted hole in the bar in order to allow for shrinkage movement of the wood of which the seat is constructed.

The operating mechanism comprises a 35 canting sill bar carried on pivotal rocking brackets which permit vertical movement of the sill bar in relation to the rear portion of the seat; this sill bar is normally held upward by springs, and is pressed downward 40 by the weight of a person resting on it when the seat is in use. The vertical movements of the sill bar are transmitted through said brackets and push rods to the shutter levers.

45 In the accompanying drawings, Figure 1 is an underneath plan of the seat fitting complete with the slide shutters shown closed; Figs. 2 and 3 longitudinal sections on line *a*—*a* and *b*—*b* Fig. 1, omitting certain parts; Fig. 4 fragment transverse section illustrating the lap joint of the slide shutters at the meeting edges thereof; and 50 Fig. 5 fragmental detail plan illustrating the mounting of the frame bars which carry 55 the slides in which the shutters move.

A is the seat panel, B the aperture therein, C and D slide shutters, Z Z' slides of folded sheet metal secured in any suitable manner to the undersides of the frame bars F F', E upwardly flanged rear edges of shutters C 60 and D, F F' frame bars, f screws holding same to underside of seat A, f' forked (or slotted) ends of frame bars which permit relative movement of the seat A and parts carried thereon so as to make the adjustment of said parts independent of shrinkage of the seat A, G G' lapping-flanges at meeting edges of shutters C and D, H H' levers connected respectively with the shutters C and D by cap studs J and J' which 65 are fixed in the shutters and move in arc slots K and K' in the levers H H'. The levers H H' are fulcrumed on pins L L' fixed in blocks set below the seat panel, and they are operated by pins M M' which work 70 in eyes in the ends of the push bars N N' which are connected at their forward ends to the rocking brackets P P'. The sill bar Q is mounted on the rocking brackets P P', which are vertically movable on the fixed 75 studs R R', and are pivotally attached at S S' to the forward ends of the push rods N N'. T T' are helical springs in compression, threaded over the rods N N' to which they are secured at U U', their rear 80 ends taking abutment against the guides V V', which are sufficiently free to allow a little lateral movement of the push rods N N', which have not an exact rectilinear motion at the rear ends owing to the curved 85 path in which the pins M M' move. W W' are lugs screwed to the underside of the seat and pressing upon the slides Z Z' to support them.

The shutters are normally closed as shown 90 in Fig. 1, a fly proof joint being made by the flanges G G' and the guides Z Z'. When the weight of a person is imposed on the sill bar Q, said bar is depressed level with the seat board A, as shown by the dotted 95 line, with the result that the push rods N N' are forced backward against the pressure of the springs T T'. This backward movement of the bars N N' is applied to the slotted levers H H' through the pins M M', and these levers acting on the shutters C and D through the cap studs J and J' force the two leaves of the shutters apart, moving them laterally, till clear of the seat 100 aperture. When the pressure of the sill 105 bar is removed, the springs T T' return the 110 shutters to their normal closed position.

bar Q is relieved, the parts are restored to normal position by means of the springs T T' with the result that the pan is immediately covered from view by the shutters 5 and sealed against entry of flies through the seat aperture.

The rising sill bar device may be used with slide shutters and intermediate operating gear constructed or arranged otherwise 10 than as shown in the drawings.

In practice, the seat, with the fittings described, is made as a unit which can be fixed readily over a flushing basin or upon a casing or frame inclosing an earth-pan.

15 What I claim as my invention and desire to secure by Letters Patent is:—

1. A closet seat comprising a seat panel having an aperture therein, a pair of shutters movable toward and away from each 20 other to cover and uncover said aperture, guides in which said shutters are slidably supported, a pair of levers fulcrumed on said panel at the rear thereof and connected to said shutters, a pair of substantially parallel rods connected to said levers and extending forwardly therefrom, and means at the front of said panel connecting said rods and movable to operate the rods to swing the levers and open the shutters.

30 2. A closet seat comprising a seat panel having an aperture therein, a pair of shutters movable toward and away from each other to cover and uncover said aperture, guides in which said shutters are slidably supported, a sill adjacent the front edge of said panel, brackets pivoted on said panel having arms carrying said sill and other arms, and levers pivoted on said panel and connected to said shutters, and rods connecting said levers to the last mentioned 35 arms of the sill brackets.

3. In a closet seat, a seat panel, a canting sill adjacent the front edge thereof, shutters slidingly mounted upon the underside of 45 said panel, longitudinally movable rods operatively connected to said sill and to said shutters to open said shutters upon said sill being depressed by the weight of a person upon the seat, and means to actuate said 50 rods to close said shutters and raise said sill when the latter is relieved of the person's weight.

4. In a closet seat, a seat panel, a canting sill adjacent the front edge thereof, shutters slidingly mounted upon the underside of 55 said panel, levers pivotally connected to said

shutters and to said panel, slidably mounted rods connected to said levers, and operatively connected to said sill, and yielding means normally urging said rods to actuate said 60 levers to close said shutters and to raise said sill whereby when said sill is depressed said rods will be moved to actuate said levers to open said shutters.

5. A closet seat comprising in combination an apertured seat panel, shutters slidably mounted upon the underside of said panel, slotted levers fulcrumed on the seat panel and connected to said shutters, a canting sill supported on pivotal brackets, push 70 rods with retiring springs articulating said brackets to said levers, pins on said shutters working in the slots in said levers, and channel guides for said shutters.

6. The combination of a closet seat panel 75 having an aperture therein shutters movable toward or away from each other to cover or uncover said aperture, supports in which said shutters are slidably mounted, levers fulcrumed on said panel at the rear end 80 thereof and connected to said shutters, substantially parallel rods connected to said levers and extending forwardly therefrom, guide means for each of said rods on said panel, spring means attached to each rod 85 and to said guide means, and pivotally mounted means at the front of the seat panel connected to said rods to actuate the same.

7. A closet seat comprising a seat panel having an aperture therein, shutters movable 90 toward or away from each other to cover or uncover said aperture, supports in which said shutters are slidably mounted, a sill adjacent the front edge of said panel, levers fulcrumed on said panel at the rear end 95 thereof and connected to said shutters, substantially parallel rods connected to said levers and extending forwardly therefrom, bell-crank connections between said rods and said sill, guide means for each of said rods 100 on said panel, and spring means attached to each rod and to said guide means, said latter means operating to close said shutters and raise said sill when same is relieved of a person's weight.

105 In testimony whereof I have signed my name to this specification in the presence of two subscribing witnesses.

GEORGE EDWARD KINCH.
